UNITED STATES PATENT OFFICE.

WILLIAM HOPWOOD, OF MANCHESTER, ENGLAND.

MEANS FOR USE IN PRACTICING THE GAME OF GOLF.

Application filed April 16, 1923. Serial No. 632,521.

To all whom it may concern:

Be it known that I, WILLIAM HOPWOOD, a subject of the King of Great Britain and Ireland, and resident of 199 Deansgate, 5 Manchester, England, have invented certain new and useful Improved Means for Use in Practicing the Game of Golf, of which the following is a specification.

This invention has for its object to provide convenient means which can be utilized in practicing the game of golf and which will serve to indicate the accuracy of the strokes of the player.

Referring to the accompanying sheet of explanatory drawings:—

Figure 1 is a front elevation and Figure 2 a plan showing one convenient arrangement of golf practicing apparatus in accordance with my invention.

20 The same reference letters in the different views indicate the same or similar parts.

As shown in the drawings, at Figures 1 and 2, I erect a screen *a* preferably of net-like form, and at the centre thereof, or at

25 any suitable position thereon, I provide a gap *b* behind which, and at a suitable distance therefrom, is supported a board or structure forming a deflector *c* set at an angle to the direction (indicated by the arrow at Figure 2) from which the ball is being played so that the said ball after striking the deflector is directed to one side behind the net or screen *a* and delivered towards a putting green or its equivalent.

30 The deflector is faced or formed of suitable material to absorb some of the energy in the ball and to divert the latter an amount depending upon the angle of incidence of

the ball thereon. Preferably, the deflector comprises a frame member enclosing a fabric or other centre which may be kept taut by a rack and pinion or screw device. The complete deflector is set and supported at the desired inclination to the screen *a* in any convenient manner; the supports are 45 not shown in the drawing.

It will be seen that with the arrangement before described, the direction and the velocity of the ball leaving the rebounding board or deflector depend upon the direction of flight and the speed of travel of the ball after being hit by the player. The game can, however, be played in a relatively confined area and gives scope for testing both the driving and putting powers of the 55 player. Several of the devices, each with its putting green, may be provided to give the equivalent of a course of several holes.

I may vary the angle of the rebound board or deflector to suit any particular requirements.

I claim:—

A golf practicing device comprising a substantially vertical screen adapted to be set up on a supporting surface and having 65 a substantially centrally disposed aperture permitting the passage of a golf ball therethrough, and a plane deflecting net of larger size than the aperture arranged directly behind the latter and set at such an angle as 70 to deflect any ball passing through the aperture to one side of the screen.

In testimony whereof I have signed my name to this specification.

WILLIAM HOPWOOD.
